UNITED STATES PATENT OFFICE.

CYRUS T. WYNNS, OF ROCKY MOUNT, NORTH CAROLINA.

SETTING DEVICE FOR SAWMILL CARRIAGES.

Application filed October 1, 1924. Serial No. 741,075.

This invention relates to sawmill machinery, and has for its object the provision of a novel automatic mechanism associated with the reciprocating log carriage whereby to advance the knees thereof, at each stroke of the carriage whereby the log will be moved step by step permitting the sawing of the successive planks or boards.

Most devices for this purpose involve a ratchet mechanism mounted on the carriage controlled by an operator riding upon the carriage, the operator being, in some instances, strapped down on account of the rapid movement of the carriage. Obviously, the well known type thus requires the services of an additional attendant for controlling the feeding of the log to the saw.

It is with the above facts in view that I have designed the present mechanism which may be constructed as an attachment to already existing saw mill carriages, the device being so arranged that after being set the feeding will be accomplished automatically and without the services of an additional attendant, thereby reducing labor and consequently the cost of production.

Another object is the provision of an automatic mechanism which may be initially set for advancing a log to any desired extent whereby planks or boards of different thicknesses may be cut.

Yet another object is the provision of manually settable and automatically operable means for receding the knees as for instance, when it is desired to reduce the thickness of the cutting as determined by a previous setting of the automatic advancing mechanism.

The invention further contemplates the general improvement of devices of this class in many structural details whereby to insure durability in service and efficiency in operation.

With the above and other objects and advantages in view, the invention consists in the details of construction and arrangement to be hereinafter more fully described and claimed, and illustrated in the accompanying drawings, in which:

- 50. Figure 1 is a plan view of the device;
- Figure 2 is a side elevation;
- Figure 3 is a section on the line 3—3 of Fig. 1;
- Figure 4 is a cross section on the line 4—4 of Fig. 1;

Figure 5 is a section on the line 5—5 of Fig. 1, and

Figure 6 is a plan view of a modified form.

Referring more particularly to the drawings, the letter A designates a sawmill carriage equipped with wheels B travelling on tracks C. This carriage is of course moved by any suitable or preferred means such as those well known in the art but such means is not illustrated as it forms no part of the present invention.

The carriage A is provided with transversely extending head blocks 10 within which are slidably mounted knees 11 which support and which are adapted to move the log on the carriage for advancing the same and consequently effecting feeding to the saw as successive planks or boards are cut. On the undersides of the knees are racks 12 with which mesh pinions 13 carried by a shaft 14 journaled at one side of the carriage. Obviously, when the shaft 14 is rotated the knees will be correspondingly moved, the extent depending upon the number of revolutions given to the shaft. The shaft 14 carries a bevel gear 15 which meshes with a bevel gear 16 on the shaft 17 which extends transversely of the carriage and which constitutes the drive shaft.

Rigidly secured on the shaft 17 is a pinion 18 and rotatable on the shaft is a bevel gear 20 meshing with the bevel gear 15. The shaft is equipped with a friction disk 21 for a purpose to be described. A bearing bracket 19 is provided for properly supporting the shaft.

Projecting from one side of the carriage are supports 22 and 23 which may be bars or the like, and these supports carry brackets 24 upon which are pivoted at 26 upstanding links 27 which have their upper ends 28 forked and pivotally connected at 29 with bearings 30 which support a shaft 31 on which is secured a drum 32 which is polygonal in cross section and which is here represented as hexagonal. The various faces of this drum carry or are formed as rack bars 33. It will be observed that these bars are of different lengths on all the different faces and the drum is rotatable whereby to bring any desired rack bar into cooperative relation with the pinion 18, depending upon the number of turns which it is desired to give the pinions 13 which move the knees. At

one end the shaft 31 is squared at 34 for engagement thereon of a suitable crank handle or wrench, such as that indicated at 35, whereby the drum may be turned to bring 5 any desired rack bar into engagement with the pinion 18. The bracket 24 is formed with a rigid projection 36 which extends upwardly and which serves as an abutment for the adjacent link 27 for limiting movement of the link in one direction under the influence of a spring 37 which has one end connected with a rod 38 in turn connected with the projection 36. Obviously, the drum 32 may swing downwardly out of engagement with the pinion 18 upon the return stroke of the carriage, the spring 37 operating to return the drum to its normal or elevated position after such return stroke is completed.

10 20 Mounted at one side of the carriage most remote from the mechanism above described, is a support 39 carrying a dial 40 inscribed with numerals which may have any arbitrary meaning such as "inches" or 25 any desired fractions thereof, and indicating the thickness of planks or boards to be cut. Rotatably mounted at the center of the dial is a shaft 41 carrying a pointer 42 movable over the dial and carrying a 30 sprocket 43 about which is trained a chain 44. On the shaft 31 is a sprocket 45 about which is trained a chain 46. The ends of the chains 44 and 46 are connected by flexible members 47 which are trained under 35 suitably grooved guide pulleys 48. Movement of the shaft 31, and consequently the drum 32, by means of the crank 35 will result in corresponding movement of the pointer 42 and as this pointer cooperates 40 with the indications on the dial 40 a visible reading will be had as to the thickness of the planks or boards to be or being cut.

Instead of turning the crank, the operator 45 may move the pointer over the dial into registration with the desired graduation so as to set the mechanism.

On the supports 22 and 23 are other brackets 49 and 50 upon which are pivoted links 51 which are in turn pivotally connected at 52 with depending projections 53 on a track 54, which is positioned beneath and adapted to engage the friction disk 21. Ordinarily, this track drops down, by gravity, into such position that it does not 55 touch the friction disk. Journally mounted transversely of the carriage trackway is a rock shaft 54^a to which one link 51 is rigidly secured. At the side of the carriage trackway most remote from the rack mechanism above described, the shaft 54^a carries a pedal 55.

Journally mounted in spaced parallel 60 relation to the shaft 54 is a similar shaft 56 having one end equipped with a pedal 57 and having its other end carrying an

arm 58 which is pivotally connected at 59 with a link 60 in turn pivoted at 61 to the adjacent link 27.

In the operation, assuming that the drum 32 has been turned to bring the desired rack 70 bar 33 into position to engage the pinion 18 it will be seen that when the carriage A is at the limit of its forward movement and starts rearwardly in the direction of the arrow, the pinion 18 will engage the rack 75 bar 33 and be rotated, thereby turning the shaft 17 and consequently the shaft 14. As the shaft 14 carries the pinions 13 meshing with the racks 12 on the knees 11 it is obvious that the latter will be moved for advancing the log. On the return stroke the pinion 18 rides idly over the rack bar 33 inasmuch as the drum 32 will be moved downwardly against the resistance of the 80 spring 37.

Whenever it is desired to recede the knees instead of advancing them, it is intended that the operator press upon the pedals 55 and 57 so as to rock the shafts 54^a and 56 and move the track 54 upwardly, and the 90 drum 32 downwardly, so that the track will engage the friction disk 21 while the rack drum disengages the pinion 18. It is evident that the disk will rotate so that the gear 20 meshing with the gear 15 will cause the 95 shaft 17 and naturally the shaft 14 to be turned in the reverse direction from the movement imparted to them when the pinion 18 engages the rack bar.

In the modified form of the device shown 100 in Figure 6, the main features of the construction are identically the same as above described but instead of a rack and pinion mechanism for moving the sawmill knees I make use of a screw device for the same purpose. In this form, the sawmill knees indicated by the numeral 62 are slidably mounted within suitable heads 63 and are formed with screw threaded bores 64 which act as nuts and within which engage screws 105 65 carrying beveled gears 66 and 67, the latter of which corresponds to the bevel gear 16 of the first described form. I also make use of a shaft 68 corresponding to the above described shaft 14 and driven in 110 exactly the same manner. At one end, this shaft 68 carries a beveled gear 69 meshing with the beveled gear 66 and at its other end it carries a bevel gear 70 meshing with the bevel gear 67 and corresponding exactly 115 to the above described bevel gear 15. In all other respects this modification is exactly the same as the first described form.

In the operation of this variation, it is observed that all the parts of the mechanism have the same action as above mentioned except that when the shaft 68 is rotated it will act to drive the bevel gears 66 and 67 and consequently turn the screws 65, which on account of being threaded into 120

the bores 64 will act to move the knees forwardly or rearwardly, as the case may be.

From the foregoing description and a study of the drawings, it will be apparent that I have thus provided a very simple feed device which will be entirely automatic and which will avoid all necessity for having an extra operator riding on the carriage. The device consequently saves time, labor and money.

While I have shown and described the preferred form of the invention it is to be understood that I reserve the right to make such changes in the construction and arrangement as will not depart from the spirit of the invention or the scope of the subjoined claims.

Having thus described the invention, I claim:

1. In combination with the reciprocatory carriage of a sawmill, knees slidably mounted thereon, rack and pinion mechanism for moving said knees, a shaft connected with said mechanism, a pinion on the shaft, a drum rotatably mounted at one side of the carriage trackway and rack bars on the drum adapted to engage the pinion.

2. In combination with the reciprocatory carriage of a sawmill, knees slidably mounted thereon, rack and pinion mechanism for moving said knees, a shaft for driving the pinions, a pinion on the shaft, a drum rotatably mounted at one side of the carriage trackway, and rack bars on the drum adapted to engage the last named pinion, the rack bars being of different lengths, and means for bringing a selected bar in position to engage the last named pinion.

3. In combination with the reciprocatory carriage of a sawmill, knees slidably mounted thereon, means for moving said knees including a shaft, a pinion on said shaft, a drum rotatably mounted at one side

of the carriage trackway, and rack bars on 45 the drum adapted to engage the pinion, said bars being of different lengths, the drum being rotatable to bring a selected bar into position to be engaged by the pinion.

4. In combination with the reciprocatory carriage of a sawmill, knees slidably mounted thereon, means for moving the knees including a drive shaft, a pinion on said shaft, a drum rotatably mounted at 55 one side of the carriage trackway, rack bars on the drum adapted to selectively engage the pinion, and means for swingably supporting the drum whereby to permit depression thereof upon the return stroke of 60 the carriage.

5. In combination with the reciprocatory carriage of a sawmill, knees slidably mounted thereon, step by step means for moving the knees including a shaft, a pinion on said shaft, a drum rotatably mounted at 65 one side of the carriage trackway, rack bars on the drum adapted to selectively engage the pinion, means swingably supporting the drum, and pedal operated means 70 connected with said means for swinging the drum into inoperative position.

6. In combination with the reciprocatory carriage of a sawmill, knees slidably mounted thereon, means for moving the 75 knees including a drive shaft, a pinion on said shaft, a drum rotatably mounted at one side of the carriage trackway, rack bars on the drum adapted to selectively engage the pinion, a friction disk on said shaft, a 80 track adapted to be brought into engagement with the friction disk, and means for simultaneously moving the drum to disengage the pinion and move the track into engagement with the friction disk.

In testimony whereof I affix my signature.

CYRUS T. WYNNS.
